Primary Examiner — Calvin E Vansant

(74) Attorney, Agent, or Firm — Crowell & Moring LLP

(57) **CLAIM**

The ornamental design for a wheel or wheel cover, as shown and described.

DESCRIPTION

FIG. 1 is a front view of a wheel or wheel cover according to the design; and,

FIG. 2 is a perspective view thereof.

The broken lines in the drawings illustrate environmental subject matter only and form no part of the claimed design.

1 Claim, 2 Drawing Sheets(56)
